UNITED STATES PATENT OFFICE.

JOHN C. KAISER, OF KENTON, OHIO.

DESIGN FOR A VEHICLE-BODY.

41,690.

Specification for Design.

Patented Aug. 15, 1911.

Application filed March 16, 1910. Serial No. 549,802. Term of patent 7 years.

To all whom it may concern:

Be it known that I, JOHN C. KAISER, a citizen of the United States, residing at Kenton, county of Hardin, State of Ohio, have invented a certain new, original, and ornamental Design for a Vehicle-Body, of which the following is a specification, reference being had therein to the accompanying drawing, forming part thereof.

Figure 1 is a side elevation of a vehicle

body, showing my new design. Fig. 2 is a perspective of the vehicle body, showing my new design.

I claim—

The ornamental design for a vehicle body as shown.

JOHN C. KAISER.

Witnesses:

HARRY L. HOPWOOD,
ELLA C. HOPWOOD.
